US00D934668S

(12) **United States Design Patent** (10) Patent No.: **US D934,668 S**
(45) Date of Patent: **** Nov. 2, 2021**

(54) **MESH WALL RIVET**

(71) Applicant: **KELTEKS d.o.o.**, Karlovac (HR)

(72) Inventors: **Srecko Petrunic**, Karlovac (HR);
Armando Maticic, Karlovac (HR)

(**) Term: **15 Years**

(21) Appl. No.: **35/510,065**

(22) Filed: **Jul. 31, 2020**

(80) **Hague Agreement Data**

Int. Filing Date: **Jul. 31, 2020**

Int. Reg. No.: **DM/209631**

Int. Reg. Date: **Jul. 31, 2020**

Int. Reg. Pub. Date: **Aug. 14, 2020**

(51) **LOC (13) Cl.** **08-08**

(52) **U.S. Cl.**

USPC **D8/386**

(58) **Field of Classification Search**

USPC D8/382, 385, 386

CPC A44B 17/0076; F16B 21/08; F16B 21/086

See application file for complete search history.
